UNITED STATES PATENT OFFICE.

WILLIAM H. ROOK, JR., OF AKRON, OHIO, ASSIGNOR TO GEORGE R. HILL, OF AKRON, OHIO.

STRUCTURAL BLOCK.

1,296,559.

Specification of Letters Patent.

Patented Mar. 4, 1919.

Application filed January 14, 1915. Serial No. 2,166.

To all whom it may concern:

Be it known that I, WILLIAM H. ROOK, Jr., a citizen of the United States, residing at Akron, in the county of Summit and State of Ohio, have invented a certain new and useful Improvement in Structural Blocks, of which the following is a full, clear, and exact description.

This invention relates to ceramic blocks for structural purposes, of the type produced from plastic clay by means of standard or approved expressing presses and cutting means.

The object of the invention is to provide for making fluid-tight joints between the butt-jointed ends of the blocks, as well on the interior as on the exterior of the structures built of such blocks.

The invention has special reference to cellular or hollow segmental blocks, particularly designed for sewer construction, and the invention will be explained by means of such blocks, although it is not intended to limit the invention to this specific use.

The invention consists of a structure or wall, such as a sewer, composed of structural blocks, each having its opposite ends rabbeted or recessed transversely in the same plane and thereby adapted when two similar blocks are alined end for end to receive a filler, which filler may be a cellular or solid block secured in the space formed by the combined rabbets of two end-butted blocks by mortar or other cementitious material; or the filler may be of plastic cement or mortar properly placed in the combined rabbets; the cementitious matter used in either case spreading over into the cells of the blocks and when dry serving as clenches in the end-joining of adjacent blocks; the adjacent rabbets and the fillers being arranged externally on the arch blocks and internally on the invert blocks of the tubular or circular structure; the invention being particularly applicable to cellular blocks, as I will proceed now to explain and finally claim.

In the accompanying drawings illustrating the invention, in the several figures of which like parts are similarly designated, Figure 1 is a perspective view of an arch block, and Fig. 2 is a perspective view of a filler block for use therewith. Fig. 3 is a perspective view of an invert block, and Fig. 4 is a perspective view of a filler block

therefor. Fig. 5 is a longitudinal section of two juxtaposed arch blocks with the filler block in place. Fig. 6 is a longitudinal section of two juxtaposed invert blocks with the filler block in place. Fig. 7 is a perspective view illustrating the formation of the joint in the arch. Fig. 8 is a perspective view illustrating the formation of the joint in the invert. Fig. 9 is a perspective view and partial section illustrating a portion of a sewer or other circular structure built of blocks of this invention. Fig. 10 is an elevation of a solid arch filling block, and Fig. 11 is a similar view of a solid invert filling block. Fig. 12 is a fragmentary longitudinal section showing an all-cement filler joint.

Explaining my invention as embodied in blocks used for sewer or other circular work, it is noted that the arch block is made in the form of a segment of a circle with an outer curved wall 1, an inner concentric curved wall 2, side walls 3 and 4, a transverse web 5 connecting the side walls and arranged about midway between the outer and inner walls, and a perpendicular partition 6 connecting the outer and inner walls and the transverse web and with said parts serving to divide the block into cells. The side walls are provided with any suitable matching means such as dovetail tongues 7 and complementary grooves 8. The side wall 3 may be made with the longitudinal edge flanges 9 and 10 at the edges of the walls 1 and 2, and the side wall 4 may have the longitudinal overhangs 11 and 12 of the grooves provided with mortar locking grooves 13 and 14. At the opposite ends of the arch block there are transverse rabbets or recesses 15 extending entirely across the blocks and from the outer wall to the top or upper surface of the web 5, and by preference these rabbets are made straight across. As shown in Figs. 5 and 7, when two similar arch blocks of this character are abutted end for end, the rabbets or recesses 15 combine to form an external cavity to receive a filler block 16 whose outer wall 17 is arched correspondingly with the arc of the outer wall 1 of the blocks and its inner wall or bottom 18 is straight to match the web 5, and its side walls 19 and 20 are made to conform to the corresponding portions of the side walls 3 and 4 of the blocks. This filler block may be divided into cells by means of

the perpendicular partitions 21, or it may be made solid, as shown in Fig. 10.

As will be understood upon reference to Figs. 5, 7, and 9, the arch blocks are assembled with their ends alined and mortar is then placed in the space or cavity formed by the rabbets, and then the filler block is inserted in said space or cavity and pressed home, displacing or distributing the mortar 10 against itself and the adjacent plane and between the perpendicular edges of the ends of the blocks and about itself. The longitudinal parallel courses of blocks are connected by means of the lateral tongues and 15 grooves and interposed mortar or other suitable cementitious material.

It is to be understood that in the construction of a circular structure, the invert block next described will be laid first, and the 20 arch blocks last, in order to effect the lateral union of the several courses of blocks entering into the circular structure.

The invert blocks, Figs. 3, 6 and 8, are precisely the same in construction as the 25 arch blocks, excepting that the rabbets or recesses instead of extending from the outside inwardly, are extended from the inside outwardly, and the filler blocks are applied on the inside instead of on the outside. Each 30 invert block has the outer wall 22, the inner wall 23, the side walls 24 and 25, the transverse web 26 connecting the side walls, the perpendicular partition 27 connecting the inner and outer walls and the transverse web, the dovetail tongue 28 and the complementary groove 29 in their respective sides 24 and 25, the flanges 30 and 31 on the side wall 24 on opposite sides of the dovetail tongue, the overhanging portions 35 32 and 33 adjacent to the groove 29, provided with the mortar-locking grooves 34 and 35, and the end rabbets or recesses 36 made, as already stated, upon the inner side of the block and extending to the upper 40 surface of the web 26 and straight across the opposite ends of the block. The filler block 37, Figs. 4, 6, 8 and 9, for these invert blocks has the segmental inner wall 38 corresponding with the inner arc of the blocks, the side walls 39 and 40 corresponding 45 in detail with the corresponding walls of the invert blocks with which it is to be used, and the straight transverse web 41, with or without the perpendicular partition 42, in accordance with whether the 50 filler block is to be cellular, Figs. 4 and 8, or solid, Fig. 11.

As illustrated in Figs. 6, 8 and 9, in the erection of a structure with these invert blocks, they are laid with their outer walls down and end for end, so that their rabbets come opposite to form an internal cavity, and then mortar is applied in the cavities so formed and the filler blocks pressed home 55 therein, thereby distributing the mortar in

the joints, in substantially the manner described with respect to the use of the filler blocks in the arch blocks.

It is to be particularly noted that the rabbets on the arch blocks at the opposite ends are arranged on the same side of the transverse web, and that the rabbets on the invert blocks are likewise on the same side of the web, so that the blocks are butt-jointed and not lap-jointed. 75

As shown in Fig. 12, instead of using a preformed filler block and mortar or cement to make the joints at the ends of the blocks, as already described, I may use an all-mortar or all-cement joint formed *in situ*, 80 which, upon hardening, will answer all of the purposes of the preformed filler blocks in many, if not all, structures. In this construction the blocks may be laid with the cementitious material 43 in contact with 85 the transverse web and extending into the cells, thus forming a clench, and struck down level with the surface of the block. This construction is particularly useful in constructing silos where there is no abrasion as in the case of flowing sewage or the like. Even for flowing matter in sewers, this all cement joint is fully equal to concrete structures.

I am aware that it has been proposed to 95 cut away the adjacent ends of structural blocks and then fill in the cut away portions with an inserted piece and mortar, but in the only instance of this construction of which I am aware, the inner walls of the 100 blocks have been made of greater thickness than the outer walls in order to provide for the cutting of the recess or rabbet in these walls. Under present practice of manufacturing structural blocks from plastic clay 105 by means of expressing presses, it has been found impractical to make the longitudinal walls of different thicknesses owing to the unequal resistance to which the masses of clay are exposed in the expressing operation, 110 since the tubes or cellular structures as they exude from the dies are deflected inward or outward in accordance with the differences in thickness, instead of coming out straight; and the tendency is for these tubes or structures to split or become deformed. Making 115 the walls of equal thickness insures the production of straight tubes, without tendency to deflect or curve, and without splitting; and as the tube is cut into block lengths, on 120 its emergence from the press, and while it is still green, the rabbets or recesses may be cut; but it will be observed that the cutting does not extend into the transverse web on either side, but ends with the adjacent surfaces of the web, and hence the blocks may be provided with the rabbets or recesses in an entirely practical way. 125

Variations in structural and operative details are within the principle of my inven- 130

tion and intended to be included in the claims herein made.

What I claim is:—

1. A tubular structure, comprising segmental blocks, each of which has an outer and an inner wall, side walls, and a transverse web connecting the side walls, said walls and web being of substantially the same thickness, the opposite ends of the block having transverse rabbets terminating with the adjacent surface of the transverse web and on the same side thereof, the blocks composing the structure being butt-jointed lengthwise and the adjacent rabbets at each butt-joint forming transverse cavities, and a filler block laid and cemented in each such cavity to close the joint between adjacent blocks.
2. A tubular structure, comprising segmental blocks, each of which has an outer and an inner wall, side walls, and a transverse web connecting the side walls, the opposite ends of the block having transverse rabbets terminating with the adjacent surface of the transverse web and on the same side thereof so that when two or more blocks are alined longitudinally the adjacent rabbets will form cavities, combined with a filler block cemented in each cavity so formed.
3. A tubular structure, comprising cellular segmental blocks, each of which has an outer and an inner wall, side walls, and a transverse web connecting the side walls, the opposite ends of the block having transverse rabbets terminating with the adjacent surface of the transverse web and on the same

side thereof, the blocks being laid end for end thereby converting their adjacent rabbets into cavities, combined with a cellular filler block cemented in each cavity so formed.

4. A sewer built of structural blocks, each block having an outer and an inner wall, side walls, and a transverse web connecting the side walls, the opposite ends of each block having transverse rabbets of substantially equal dimensions and extending inwardly to the adjacent side of the web and in the same longitudinal plane, the rabbets of adjacent blocks when the blocks are laid end for end forming a cavity, and a filler applied in said cavity and closing the joint between the ends of the blocks and forming a clench with such block ends.

5. A structure of the character described, comprising structural blocks, each block having its opposite ends provided with transverse rabbets of substantially equal dimensions and extending inwardly and in the same longitudinal plane, the rabbets of adjacent blocks when laid end for end forming a cavity, and a filler applied in said cavity and thereby closing the joint between the ends of adjacent blocks and forming a clench with such block ends.

In testimony whereof I have hereunto set my hand this ninth day of January A. D. 1915.
